UNITED STATES PATENT OFFICE.

JOHN M. GILMORE, OF CHICAGO, ILLINOIS.

MOTOR.

Application filed December 16, 1925. Serial No. 75,735.

This invention relates to improvements in water or fluid motors and more especially to such a motor adapted for use in connection with a mechanical tooth brush.

5 One of the features of my invention is the making of such a motor which is simple and cheap in construction and yet serviceable and durable.

Another important feature of the invention 10 is the making of such a motor which is reversible. This is especially desirable in a motor to be used with a tooth brush as such a device is more effective when the action is reversed occasionally than when the action 15 is constantly in one direction. The reversing of the motor is very easily accomplished without requiring difficult adjustments.

Other features and advantages of my invention will appear more fully as I proceed 20 with my specification.

In that form of device embodying the features of my invention, shown in the accompanying drawings, Figure 1 is a vertical sectional view of the motor showing the 25 same in use as a tooth brush, Fig. 2 is a view taken as indicated by the line 2 of Fig. 1; Fig. 3 is a view taken as indicated by the line 3 of Fig. 1; and Fig. 4 is a view in side elevation of the same.

30 As shown in the drawings, the device comprises a substantially cylindrical casing 10 provided with a water inlet nipple 11 to which a water supply tube 42 is attached in the usual manner. The lower end of the 35 casing 10 as indicated by 10^a is open and permits the discharge of water. The upper end of the casing 10 is closed as indicated by 10^b with the exception of a small central opening through which projects the hollow 40 rotor shaft 12 which carries the brush 13. The brush 13 is provided with a shank 14 adapted to be inserted in the end of the rotor shaft 12 and held therein by frictional engagement.

45 The lower bearing for the rotor shaft 12 is formed by the upper end of a screw 15 which is threaded through the transversely arranged tube 16 which is held in place in the casing 10 by means of the two screws 17, 17. The screw 15 is held in position by the 50 lock nuts 18, 18. The lower end of the screw 15 is further held in position by means of the wire 19 which is twisted a few times around the lower end of the screw and thence carried over to the walls of the casing 55

10 and thence bent downwardly as indicated by 19^a. This wire is preferably arranged at right angles to the tube 16 in order to prevent rotation thereof on the screws 17. The upper end of the screw 15 carries a block 60 20 formed with a slight concavity in its upper surface in which rests the lower end of the pin 21 which is inserted in the rotor shaft 12 in order to form a bearing therefor.

The rotor shaft 12 carries a rotor wheel 65 22 here shown as provided with six vanes 23 adapted to be engaged by the incoming stream of water and rotated thereby.

Where the nipple 11 enters the casing 10 there is provided a pivoted valve plate 24, 70 70 pivoted on the wire 25 at one edge. The valve plate 24 is adapted to take either one of two positions as shown in Fig. 2, one of the positions being indicated by the solid lines and the other by the broken lines in 75 this figure.

It will be seen that the valve plate 24 will operate to deflect the stream of water entering the casing 10 from the nipple 11 to a direction tangential with respect to the rotor wheel 22. The side of the wheel to which the direction will be tangential will depend upon the position of the valve 24 and by changing the position of the valve the direction of rotation may be changed.

In the operation of the device, the water is turned on and the pressure of water will drive the valve plate 24 to one side or to the other, giving a certain direction of rotation to the motor. In the event it is desired to 80 reverse the rotation of the motor, the water is momentarily turned off and the motor laid over on one side slightly, in order to cause the valve plate 24 to fall to the opposite side from this last position. The water is again 85 turned on and the flow of water will hold the valve to the side, and the direction of rotation of the motor will be changed. In this manner it is possible to reverse the direction 90 of rotation of the motor as frequently as desired.

It will be seen that the shape of the casing for the motor especially adapts it for use as a tooth brush. By having the rotor shaft 105 projecting from the upper closed end of the cylindrical casing, the same may be easily inserted in the mouth of a user while leaning over a washbowl. When thus in use, the water escapes from the lower open end of the cylindrical casing into the washbowl. 110

The casing being cylindrical is easily held in the hand and thus is suitable as a handle for the motor.

While I have shown and described certain embodiments of my invention, it is to be understood that it is capable of many modifications. Changes, therefore, in the construction and arrangement may be made without departing from the spirit and scope of the invention as disclosed in the appended claim, in which it is my intention to claim all novelty inherent in my invention as broadly as possible in view of the prior art.

What I claim as new, and desire to secure by Letters Patent, is:

In a device of the character described, a substantially cylindrical casing constituting

a handle, said casing being open at the bottom and closed at the top, a shaft in said casing to operate a tool, a rotor on said shaft, a water inlet nipple on said casing, and a loosely pivoted valve in said nipple for directing water which enters the casing from the nipple in a direction tangential to either side of the rotor whereby said water entering the casing through said nipple operates the rotor and its shaft and escapes through the lower end of said casing, the shifting of said valve being controlled through the tilting of said casing.

In testimony whereof, I have hereunto set my hand this 8th day of December, 1925.

JOHN M. GILMORE.
